BAG CLOSING APPARATUS

Frederick F. Zeier, Nyack, N. Y., assignor, by
mesne assignments, to Willcox & Gibbs Sew-
ing Machine Co., New York, N. Y., a corpora-
tion of New York

Application February 15, 1934, Serial No. 711,404

2 Claims. (Cl. 112—11)

This invention relates to improved apparatus for stitching and closing the tops of filled bags and like receptacles.

Although there have been numerous efforts in the past to provide apparatus for closing the open tops of filled bags, most of these efforts have resulted in machines embodying complicated conveyor apparatus for moving the work to the bag closing element, or to units in which the filled bag must be lifted from the floor to a table and manually moved across the table or moved with the table through a sewing mechanism, and in all of these relative manual adjustment vertically between the conveyor or table and the bag closing element is necessary, when the height of the bag, or the contents therein, is altered in vertical height. Nearly all of these previous efforts resulted in large, cumbersome, and costly devices which could not be moved conveniently about from place to place.

It is an object of the present invention to provide bag closing apparatus which may be moved about from place to place very readily and which lends itself to the closing of bags of various heights.

It is a further object of the present invention to provide a simple and inexpensive stitching unit for closing the mouths of filled bags, which will be easy to install and to operate.

Another object is to provide a simple yet very efficient cut-off adapted to automatically cut the free line of loose stitching between successively closed bags.

A further object of the present invention is to provide a bag closing apparatus which may be quickly changed and semi-fixed to receive and operate upon bags of various heights, and semi-fixed in the new or changed height without the necessity of loosening, setting, and then locking some yoke or equivalent arrangement.

Some of the features of the present invention include the provision of a single control adapted to easily and quickly move the stitching unit perpendicularly for bags of various heights, and horizontally across the top of the bag to close it by simple, one-handed operation, and at the same time and with the same hand to be able to operate a switch to control the electric motor, and to operate and close a clutch or other driving connection between the motor and the sewing head.

In addition to this, the present invention provides the advantageous feature of regulating the speed of operation on the sewing head with the same hand and at the same time as the various functions just described are accomplished.

Another feature of the present invention is the provision of a suspension apparatus adapted to swag (hang heavily) rather than dangle a stitching unit and a structure for conditioning and operating various instrumentalities on the unit without danger of adversely shifting the stitching head relative to the work.

A further feature is the provision of a suspension apparatus adapted to automatically lift the stitching unit to a raised position without the use of a weight.

Yet another feature of the present invention is the provision of a brake associated with the controlling mechanism adapted to be applied automatically as the clutch and switch are connected.

A further feature is the provision of a single control adapted to shift the main stitching unit vertically and horizontally and more particularly to close a switch for an electric motor, and a clutch connecting the motor to a sewing machine in timed relation; viz., start the motor just prior to closing the clutch and thereby lessen the load on the motor and on the power line by obtaining motor momentum prior to imposing a load on the motor, and to break the clutch connection just prior to stopping the motor so that inertia of the motor will not continue to drive the sewing machine after the switch and motor circuit is opened.

Yet another feature is the provision of a unitary, portable device which may be moved by one hand of the operator while the other hand is used to hold or locate the article to be worked upon, which embodies in a unitary device a stitching mechanism, a twine supply, electrical connection and control readily shiftable into various locations and heights.

In the drawings:

Figure 1 is a view showing a filling station with the bag closing machine of the present invention located conveniently, and shows the semi-portable suspension apparatus provided by the present invention.

Fig. 2 is an enlarged side view of the portable sewing unit provided by the present invention, and shows the single control and the various structural details for starting and stopping the unit and for governing the speed.

Fig. 3 is a side view of the mechanism shown in Fig. 2.

Fig. 4 is a modified form of the present invention, with an intermediate belt drive between the electric motor and the sewing head, and a modified form of control.

Fig. 5 is a front view of that form of the present invention shown in Fig. 4.

Fig. 6 is a fragmentary view of the split clutch pulley and the control therefor provided by the 5 present invention.

Fig. 7 is a schematic view showing the clutch and switch control for that form of the invention shown in Figs. 4 through 6.

Fig. 8 is a side view similar to Fig. 1, but shows 10 the apparatus of the present invention as a fully portable unit.

Fig. 9 is a top view of the yoke.

Fig. 10 is a detailed view of a modified form 15 of yoke.

Fig. 11 is a combined front and side view of a modified form of suspension apparatus.

Fig. 12 is a detailed view of the cut-off.

Fig. 13 is a detail view of the handle.

A detailed description now follows:

In Fig. 1 there is shown a representative filling 20 station including a bin 12 and a spout 13 adapted to be inserted into the open mouths of bags 14 and to fill the latter with flour, sugar, or other commodities. This bin and spout may, in the 25 now known manner, be associated with a larger bin above a ceiling 15 and provided with an automatic weighing or control arrangement adapted to intermittently pass a predetermined quantity of the commodity to the bags as the latter 30 are slid upon the spout.

The present invention provides a novel suspension apparatus 16 which, as at present preferred, 35 comprises a plurality of brackets 17 suitably secured to side walls 18 adapted to support a rail 19 to provide a runway for rollers 20 on a carriage 21 and through a loop 22 and hook 23 support a frame 24 having one or more rollers 25 forming a free running connection for a counterbalancing apparatus 26 portion of the suspension 40 apparatus 16 adapted to semi-fixedly support a universally movable stitching unit 27 at various heights relative to a floor upon which filled bags 14 are located. The rail 19 and carriage 21 permit movement of the movable stitching unit horizontally across the floor to various 45 groups of bags.

The counterbalancing apparatus 26 includes 50 a cable 28 secured to the stitching unit 27 supporting a frame 30 through a connection 29 and a counterbalancing weight 31 at its opposite end which may be made solid or may be made hollow with a screw threaded cap 32 at the end so that the hollow section may be filled with shot or other material in order to vary the weight; 55 for example, if it is desired to have the weight 31 automatically move the stitching unit 27 vertically clear of the bags each time the stitching operation on an individual bag is completed. Preferably the weight 31 is made of considerable 60 length, as shown, in order to be more steady in its operation.

If the stitching unit is to be used in a localized 65 area of the floor, for example, an area overlying the tops of five or six bags and therefore not requiring horizontal movement of the carriage 21 in the rail 19, smooth action of the weight 31 and consequently of the stitching unit 27 may be 70 further insured by swinging a yoke 33 (shown best in Fig. 9) on the weight into sliding engagement with a vertically disposed rod 34 supported at one of its ends in a suitable notch or aperture 35 in the floor, and having its upper end supported in a suitable aperture 36 in the bracket 75 17. The yoke 33 is preferably made as shown in Fig. 9, with ears 37 adapted to clear the bar

34 when swung into operative position relative to the bar, and to move into the closed position shown by dot and dash lines 38' when a screw 38 is tightened with a wing-nut 39', to have a large loop 39 grip the weight 31 and to have a 5 Fig. 10, adapted to yieldingly grip the bar 34.

This yoke 33 encircling the bar 34 prevents the weight 31 from swaying and thereby tends to hold the stitching unit in a semi-fixed position, and this latter advantage may be further 10 obtained by the provision of spring fingers 40' on the loop 40 as shown on the modified yoke in Fig. 10, adapted to yieldingly grip the bar 34.

It is possible to move the entire mechanism to various horizontal positions across the floor by 15 merely lifting the rod 34 out of the notch 35 and pulling the lower end of the bar across the top of the floor until the upper end slides out of the aperture 36, and reversing this operation to place the rod in one of the several duplicate rail supporting brackets 17 and cooperating floor notches 35, or by providing a vertically disposed rod in each of the brackets and cooperating notches in the floor, and merely disconnecting the yoke 33 from one, moving the carriage to another 20 horizontal location, and then connecting the yoke again to the rod closest to the desired location.

When it is desired to move the carriage quickly to a large number of locations over the floor without changing the yoke connection 33, it is merely 25 necessary to swing the yoke out of engagement with the rod 34.

In order to provide a universally movable sewing mechanism which may be moved and controlled very easily, a number of problems are 30 involved. The present invention has mastered these very well with a number of novel structural details. In one form, that shown in Figs. 1 through 3, this has been accomplished by the provision of the stitching unit 27 on the substantially inverted, L-shaped main frame 30 including a base section 41 and an overhanging arm 42 with a table 43 near the lower end of the base adapted to have a sewing head 44 connected to it as by screws (not shown) and an upper table 45 for supporting an electric motor 46 secured thereto, with an armature shaft 47 in co-axial alignment with a main drive shaft 48 on the sewing machine unit 44. The base 30 and the tables 43 and 45 thereon are, according to the 35 present invention, offset relative to the connection 29 sufficiently to bring the center of gravity of the vertically suspended electric motor and sewing machine head centrally relative to the cable 28, thereby maintaining the suspended unit 40 in a perpendicular plane and minimizing the 45 possibility of any swinging or pendulum-like 50 action.

The sewing machine unit 44 is provided with a needle-driving pitman 49 and needle lever 50 adapted to operate a needle bar 51 and needle 52, and is provided with a presser foot 53, co-acting 55 with a usual feeding mechanism generally indicated by 54. A four motion, feed actuating means is indicated by 55. All of these are of the usual and well-known Metropolitan sewing machine construction. The sewing machine is further provided with a cover plate 56 in the form of a cylindrical bed over which the bags 14 feed during the stitching operation.

Operation of the stitching unit 44 is, according 60 to the present invention, facilitated by the provision of a support 57 on the frame 30 adapted to support a plurality of spools 58 of sewing twine 59 and a twine guide 59', held by the 65 70 75

frame in fixed relation to the operating parts of the sewing machine at all times. Thus, there is no danger of pulling the twine from the ordinary tension rolls on the sewing unit or of twisting the threads around the unit, as would certainly occur if the rolls were not adapted to move coordinately with the universally movable sewing unit.

Current for the electric motor 46 is provided through an extension cord 60 having a conventional outlet plug connection 60' to a suitable source of current, with the cord extending to the top of the unit 27 and thence connecting with the motor through a switch 61. The switch is of the conventional one way type having an arm 62 normally held in retracted, switch-opening position by a usual inner spring in order to keep the current from reaching the motor, but is adapted to be moved into the advanced position 62', shown by dot and dash lines, against the continuous spring pressure in order to close the circuit to the motor.

A particularly novel structure is provided by the present invention for moving the stitching unit 27 vertically and horizontally, for starting and stopping the electric motor 46, and for variable control of a driving connection 63 between the motor and sewing head.

In that form of the invention shown in Figs. 30 1 through 3 the driving connection 63 includes a cup cone 64 fixed to the outer end of the main drive shaft 48 of the sewing machine, and a coaxially aligned disk cone 65 having a spline connection 47' on the armature shaft 47 and slidable 35 axially thereon into and out of driving engagement with the cup cone.

Operation of the driving connection 63 is effected by a crank-arm 66, fulcrumed on a pin 67 in an abutment 67' on the frame 30, having a yoke 68 entering a collar 69 on the disk cone 65 and having a bar 70 paralleling the base 41 with a connection 71 at its lower end to an arm 72 secured to a rod 73 portion of a handle 74. The handle is provided with a cut-out, center section 74' to accommodate the hand of a user, and is held in the frame with a nut 73' on the outer end of the rod 73. By having the parts so arranged that the arcuately movable rod 73 on the handle 74 is centrally disposed relative to the latter, a positive, balanced control of the entire stitching unit 27 is achieved in moving it vertically and horizontally, and there is no tendency to tilt the unit from the perpendicular as would occur if the handle extended to one side only of the rod. Although the connection 71 may be a direct pin and slot connection between the bar 70 and arm 72, it is preferably made with a link (as shown), between the two in order to insure a smoother action.

A spring 75 connected to the frame 30 on a pin 75' at one of its ends and at its opposite end to an extension 76 on the crank arm 66 serves to move the crank arm in a clockwise direction about the fulcrum 67, as viewed in Fig. 2, and thereby causes the yoke 68 to move the associated cone disk 65 outwardly of the cup cone 64 to break the driving connection 63 therebetween. However, in order to close the driving connection it is merely necessary to turn the handle 74 in a clockwise direction, whereupon the arm 72 through the connection 71 moves the bar 70 and associated yoke 68 in a counter-clockwise direction against the tension of the spring 75 and moves the disk cone along the spline connection 47' first into slipping engage-

ment with the cup cone, and upon further turning, into solid connection with the cup cone in order to drive the main shaft 48 and all the associated moving parts of the sewing machine at the same speed as the electric motor.

In addition, the crank arm 66, according to the present invention, is arranged to automatically operate the switch 61 and thereby control the motor 46. For this purpose a link 77, which may be in the form of a bead chain, is connected 10 to the yoke 68 and the arm 62 portion of the switch and is so arranged that it moves the arm 62 into the dot and dash position 62' shown in Fig. 2 in order to close the switch, and thereby passes current to the electric motor. Preferably 15 the link 77 and arm 62 are adjusted to close the switch upon initial counter-clockwise movement of the yoke 68 so that the motor 46 is started and, because it is free of load, brought up to speed prior to the disk cone 65 being brought into even 20 slipping engagement with the cup cone 64, and is arranged to break the driving connection 63 prior to disconnection of the electric motor so that inertia of the latter will not continue to operate the sewing machine.

Thus, the present invention provides a compact unitary structure including: the twine supply for the sewing machine; an integral electric motor; electrical connections for starting and stopping the motor; and a driving connection, with a simple one-hand control adapted to move the complete unit in a balanced manner vertically and horizontally; and is structurally arranged so that the same hand and handle may be used to condition the electrical connections and to control 35 the driving connection.

Figs. 4 through 7 show a modified form of stitching unit 27' which embodies practically all of the advantages of the first form already described in detail, but in addition has the advantage of being more satisfactory for use in places having but limited head room, since the entire unit is much shorter vertically and consequently the bottom thereof will be at a greater height from the floor when in the raised position so that there is no danger of striking it with one's head, and it also has the advantage of an indirect driving connection 78 between the motor and the sewing machine, rather than the substantially direct driving connection 63 of the first form of the invention, permitting the use of different size pulleys in order to change the speed of the sewing machine unit to various ratios, which may be desirable when there is a change of material forming the bag or a change 55 in the thickness of the material.

This form of the invention includes a very different form of base 79 and control 80, but includes exactly the same sewing machine unit 44, electric motor 46, and switch 61 as the first form of the invention. The base member is preferably a very short, substantially rectangular block with the sewing machine 44 secured to one side and the electric motor 46 secured to the opposite side by screws 81. A connecting plate 82 extends upwardly from the center of the base for connection (if preferred, to the cable 28 of the counter-balancing mechanism 26 of the first form of the invention), as shown, to a modified form of counter-balancing apparatus 26' through a loop 82' 70 to a cable 28' extending around a single pulley 83 to a weight 81.

This form of the invention provides twine supports 57' for rolls 58 of twine 59 directly upon the cable 28' and resting upon the loop connec- 75

tion 82', and a thread guide 84 secured to the cable above the spools 58 and spool supports 57'. Since the loop 82' rotates the cable, should the stitching unit 27' be turned axially, the thread support 57' and guide 84 would be turned axially an equivalent amount so that there is no danger of twisting the thread relative to the sewing machine unit. The motor 46, mounted on substantially the same horizontal plane as the sewing machine 44 and on the opposite side of the base member 78 and connecting plate 82, balances the complete stitching unit 27' in a proper perpendicular plane.

The driving connection 78 of novel form is provided by this form of the invention and includes a solid pulley 85 on the shaft of the sewing machine and a split pulley clutch 86 on the armature shaft 47 of the motor with a V belt 87 connection extending between the two. This split pulley clutch 20 may be seen best by referring to Fig. 6, and includes a fixed half 88 of the split pulley secured to the armature shaft with a set screw 88' and is provided with a hub 89 upon which a free half 90 of the split pulley is supported for axial and 25 rotative movement. A housing 90' is provided in the outer face of the free half 90 to support a thrust bearing 92 for eliminating friction when the split pulley half is moved from the non-driving position shown by dot and dash lines 91 30 into the driving position shown in Fig. 6.

Control of the split pulley clutch 86 is effected in this form of the invention by a lever 93 with forked fingers 94 underlying the thrust bearing 92 fulcrumed on a pin 95 in a bracket 96 suitably 35 secured to the top end of the base member 78, or formed integral therewith, and having a single finger 93' connected by a link 97 to a bell-crank 98 on the bracket 96 and thence through a link 99 to a control member 100 pivoted on a stud 101 40 in a slot 102 in a main handle 103. In this form of the invention the handle is rigidly secured to the frame 79 by side plates 104 and screws 105.

Preferably a brake 118, as shown in Figs. 4, 6 and 7, is provided on the outer end of the finger 45 93', adapted to move into engagement with the side of the solid pulley 85 in order to bring the sewing head 44 to a dead stop quickly when the driving connection 78 is broken. When this brake is included a spring 119 is provided between 50 the motor 46 and yoke 94 to pull the brake against the pulley with the proper degree of pressure.

Preferably, as with the first form of the invention, the clutch controlling yoke 93 has a link connection 77 with a switch 61 adapted to pass current from a feed wire 60'. The switch is of the one-way type, being resiliently held in the normal position shown in Fig. 4 by an inner spring, and being necessarily held against spring pressure in the operative or circuit closing position shown by dot and dash lines 62'.

The weight of the free half 90 of the split pulley, the contracting pull of the V belt 87, and the spring tension of the switch arm 62 all serve to hold the driving connection control 80 in the normal, inoperative position shown in Figs. 4 and 7.

Movement of the stitching unit 27' into working position is effected by merely grasping the handle 103 and pulling the unit cable 28' over the pulley 88 into the desired vertical and horizontal stations, without gripping the handle hard enough to pull the control member 100 into the slot 102, aligning the feed dog 54 and needle 52 with the top of a bag 14 and then gripping the control member 100 to move it inwardly of the slot, whereupon the link 99, bell crank 98, link 97, and lever

93 in their initial movement operate the yoke 94' and link 77 to close the switch 61 to start the motor, and upon further movement cause the split half 90 to move toward the solid half 88 of the split pulley 86 to grip and tighten the belt 5 gradually relative to the solid half and thereby effect at first a slipping belt connection with the sewing machine unit 44, and upon final tightening of the control member relative to the handle, effecting a solid or full driving connection between the two. When the end of the bag is reached it is necessary merely to loosen one's grip 10 on the control member 100, whereupon the pull 15 of the belt 87 and weight of the half 90 moves the yoke 94 in a clockwise direction to free the belt again on the split pulley and coordinately open the switch again to stop the motor.

As with the first form of the invention, the handle 103 and control 80 are arranged so that the complete stitching unit 27' is not tilted or 20 twisted unduly in the regular manipulation; both vertical and horizontal placement of the unit is effected in a very balanced manner, and the control of the switch 61 and of the driving connection 18 is accomplished without twisting the unit or 25 causing it to swing in any manner.

Fig. 8 shows a further modified form of the present invention which may be used equally well with both forms of the invention just described in detail, and illustrates very clearly the fully 30 portable characteristic of the present invention. It discloses a truck 106 which may be moved about from place to place on wheels 107 and is provided with an upright standard 108 having an overhanging arm 109. This arm may be 35 arcuately movable on a thrust bearing 110 within a housing 111 on a table of the truck, or may be rigidly secured relative to the truck. The overhanging arm is provided with an outer hook 112 adapted to receive the loop 22 in the frame 40 24 of the counter-balancing apparatus 26 or to receive the hook 113 of the single pulley device 83 of the second form of counter weight apparatus 26'. This form of the invention enables the stitching unit to be used in various areas in 45 the one room, or to be moved from one room or one plant to another without inconvenience.

A bar 114, secured at its lower end to a finger 115 on the standard 108 and at its upper end in a suitable aperture 116 in the overhanging arm 108, is included to provide the semi-fixed connection. Spacing of the outer hook 112 relative to the bar 114 is such that the frame 24, when in the hook, locates the weight 31 properly 50 relative to the bar 114 so that the yoke 33 of 55 Fig. 9, or yoke with fingers 40' in Fig. 10, may be secured to the weight and encircle the bar to provide a semi-fixed connection as described hereinbefore. An inner hook 117 on the arm 109 serves similarly to locate the weight 31 of the 60 single pulley 83 type of counter-balancing apparatus 26' properly relative to the bar 114 so that it too may include the yokes to provide a semi-fixed connection.

In those cases where it is preferred not to have 65 a hanging counterweight for pulling the unit 27 or 27' to the raised position, the present invention provides an automatic suspension device 120, as shown in Fig. 11, which includes a drum 121 rotatably mounted on a shaft 122 in a standard 70 123 upon which a stitching unit supporting cable 124 is affixed and wound to lift the unit and unwind to lower it. The drum is provided with a recess 125 at one end housing a substantial flat spring 126 which is affixed at its outer end 75

to the drum and at its inner end to the support 123. The size and set of the spring are preferably proportioned to pull the stitching unit to the raised position when the unit is released by 5 the operator, but in effect counter-balance the unit so that very little manual effort is required to pull the stitching unit down into the operative or working position.

The degree of tightness with which the coils 10 of the spring are tightened may be such that it serves to support the unit in any desired perpendicular position, yet not raise it. The standard is provided with bolts 127 for securing it to the ceiling 15 or carrier 23, and may be provided 15 with a hook, similar to the hook 113, for securing it to the mobile or semimobile apparatus similar to those already described.

Both main forms of the invention may be, and, as shown, are provided with a novel cut-off device 20 vice 128 adapted to snip the free line of stitching between successive bags 14, or the like, worked upon by the stitching unit 44. Because the work table 56 is vertically arranged a special problem is involved in providing a cut-off apparatus.

25 As shown in Figs. 2, 4, 5 and 12, the structure provided by the present invention and now preferred comprises a substantially L or V-shaped movable member 129 pivoted on the main table 56 by a stud 130 with a movable shear blade 131 integral therewith or affixed thereto, and a co-operating stationary shear blade 132 in the form of a removable plate affixed to the table by screws 133. The other end of the movable member 129 includes a U-shaped yoke 134 adapted to receive 30 an eccentric 135 on the end of the main shaft 48 for moving the shear blade into engagement with the shear plate continuously. Any surplusage of thread between the bags drops vertically along the table 56 between the shear blade and 35 shear plate to be clipped thereby. Because the cut-off device is constructed to permit operation close to the line of stitching, twine may be saved. Also, it is very easy to guide the chain of stitching into the path of the cutting edges because 40 the cut-off device is located at the bottom end of the machine.

That form of the invention shown in Figs. 4 through 7 may also be provided with a shield 136 adapted to enclose the driving connection 18 and enclose the crank 93 both for the operator's safety and to prevent the belt 88 from whipping and riding off the pulley 86 when the latter is opened. The shield, shown best in Figs. 4 and 5, is preferably held in place by lancing an ear 137 upwardly from a face 136 thereof and securing it to the plate 82 with a screw 138. The 10 inside of the shield is provided with a cushion 139, of felt or the like, against which the belt may strike when it becomes slack. It is spaced from the outside diameter of the pulley 86 less than the thickness of the belt 87 and thereby 15 prevents the slack belt from riding off the pulley. The cushion prevents noise and wear on the belt, while the shield not only protects the operator from injury, but keeps the belt under control during operation of the machine. 20

Other variations and modifications may be made within the scope of this invention, and portions of the improvements may be used without others.

I claim:

1. In an apparatus of the character described, the combination of a suspension apparatus; a bar associated with said apparatus; a universally movable stitching unit; a counter-balancing mechanism for supporting said stitching unit; a weight in said counter-balancing apparatus; and a yoke adapted to be secured upon the weight and to yieldingly grip the bar for semifixedly holding said portable stitching unit. 25

2. In an apparatus of the character described, the combination of a standard; a bar associated with said standard; a pulley supported on said standard; a universally movable stitching unit; a weight; a cable extending over said pulley and connecting said weight to said stitching unit; and a yoke on said weight and on said bar and adapted to yieldingly grip the bar for semi-fixedly holding said universally movable stitching unit. 30 40

FREDERICK F. ZEIER. 45

CERTIFICATE OF CORRECTION.

Patent No. 2,146,279.

February 7, 1939.

FREDERICK F. ZEIER.

It is hereby certified that error appears in the printed specification of the above numbered patent requiring correction as follows: Page 2, second column, line 6, strike out the words "Fig. 10, adapted to yieldingly" and insert instead small loop 40 encircle yet not; and that the said Letters Patent should be read with this correction therein that the same may conform to the record of the case in the Patent Office.

Signed and sealed this 4th day of April, A. D. 1939.

Henry Van Arsdale

(Seal)

Acting Commissioner of Patents.

to the drum and at its inner end to the support 123. The size and set of the spring are preferably proportioned to pull the stitching unit to the raised position when the unit is released by 5 the operator, but in effect counter-balance the unit so that very little manual effort is required to pull the stitching unit down into the operative or working position.

The degree of tightness with which the coils 10 of the spring are tightened may be such that it serves to support the unit in any desired perpendicular position, yet not raise it. The standard is provided with bolts 127 for securing it to the ceiling 15 or carrier 23, and may be provided 15 with a hook, similar to the hook 113, for securing it to the mobile or semimobile apparatus similar to those already described.

Both main forms of the invention may be, and, as shown, are provided with a novel cut-off device 20 vice 128 adapted to snip the free line of stitching between successive bags 14, or the like, worked upon by the stitching unit 44. Because the work table 56 is vertically arranged a special problem is involved in providing a cut-off apparatus.

25 As shown in Figs. 2, 4, 5 and 12, the structure provided by the present invention and now preferred comprises a substantially L or V-shaped movable member 129 pivoted on the main table 56 by a stud 130 with a movable shear blade 131 integral therewith or affixed thereto, and a co-operating stationary shear blade 132 in the form of a removable plate affixed to the table by screws 133. The other end of the movable member 129 includes a U-shaped yoke 134 adapted to receive 30 an eccentric 135 on the end of the main shaft 48 for moving the shear blade into engagement with the shear plate continuously. Any surplusage of thread between the bags drops vertically along the table 56 between the shear blade and 35 shear plate to be clipped thereby. Because the cut-off device is constructed to permit operation close to the line of stitching, twine may be saved. Also, it is very easy to guide the chain of stitching into the path of the cutting edges because 40 the cut-off device is located at the bottom end of the machine.

That form of the invention shown in Figs. 4 through 7 may also be provided with a shield 136 adapted to enclose the driving connection 18 and enclose the crank 93 both for the operator's safety and to prevent the belt 88 from whipping and riding off the pulley 86 when the latter is opened. The shield, shown best in Figs. 4 and 5, is preferably held in place by lancing an ear 137 upwardly from a face 136 thereof and securing it to the plate 82 with a screw 138. The 10 inside of the shield is provided with a cushion 139, of felt or the like, against which the belt may strike when it becomes slack. It is spaced from the outside diameter of the pulley 86 less than the thickness of the belt 87 and thereby 15 prevents the slack belt from riding off the pulley. The cushion prevents noise and wear on the belt, while the shield not only protects the operator from injury, but keeps the belt under control during operation of the machine. 20

Other variations and modifications may be made within the scope of this invention, and portions of the improvements may be used without others.

I claim:

1. In an apparatus of the character described, the combination of a suspension apparatus; a bar associated with said apparatus; a universally movable stitching unit; a counter-balancing mechanism for supporting said stitching unit; a weight in said counter-balancing apparatus; and a yoke adapted to be secured upon the weight and to yieldingly grip the bar for semifixedly holding said portable stitching unit. 25

2. In an apparatus of the character described, the combination of a standard; a bar associated with said standard; a pulley supported on said standard; a universally movable stitching unit; a weight; a cable extending over said pulley and connecting said weight to said stitching unit; and a yoke on said weight and on said bar and adapted to yieldingly grip the bar for semi-fixedly holding said universally movable stitching unit. 30 40

FREDERICK F. ZEIER. 45

CERTIFICATE OF CORRECTION.

Patent No. 2,146,279.

February 7, 1939.

FREDERICK F. ZEIER.

It is hereby certified that error appears in the printed specification of the above numbered patent requiring correction as follows: Page 2, second column, line 6, strike out the words "Fig. 10, adapted to yieldingly" and insert instead small loop 40 encircle yet not; and that the said Letters Patent should be read with this correction therein that the same may conform to the record of the case in the Patent Office.

Signed and sealed this 4th day of April, A. D. 1939.

Henry Van Arsdale

(Seal)

Acting Commissioner of Patents.
